United States Patent

Des. 241,628
Patented Sept. 28, 1976

241,628

LINEAR CLOCK

James R. Bailey, 4020 N. Pioneer Ave.,
Chicago, Ill. 60634

Filed Apr. 25, 1975, Ser. No. 571,649

Term of patent 14 years

Int. Cl. D10—01

U.S. Cl. D10—15

FIG. 1

FIG. 2

FIG. 1 is a front perspective view of a linear clock showing my new design; and

FIG. 2 is a front perspective view of another embodiment of my new design of FIG. 1.

The top and right sides of FIGS. 1 and 2 are identical with those shown, the rears being flat, plain and unornamented.

I claim:

The ornamental design for a linear clock, as shown and described.
